UNITED STATES PATENT OFFICE.

CHARLES HENRY DILLON, OF NORTH ATTLEBOROUGH, MASSACHUSETTS,
ASSIGNOR OF ONE-HALF TO JOHN Q. HENNIGAN, OF SAME PLACE.

FLUSHING-VALVE.

SPECIFICATION forming part of Letters Patent No. 410,541, dated September 3, 1889.

Application filed April 23, 1889. Serial No. 308,326. (No model.)

To all whom it may concern:

Be it known that I, CHARLES HENRY DILLON, of North Attleborough, county of Bristol, State of Massachusetts, have invented an Improvement in Flushing-Valves, of which the following description, in connection with the accompanying drawings, is a specification, like letters on the drawings representing like parts.

10 This invention relates to flushing-valves especially adapted to be used in the tanks of water-closets, and has for its object to construct the valve as will be described, whereby a water seal is provided against the escape 15 of sewer-gas into the house or building.

My improved flushing-valve is of the class known as "slow-closing valves," and is simple in construction, compact in size, and durable in operation.

20 The peculiar features in which my invention consists will be hereinafter pointed out in the claims at the end of this specification.

Figure 1 is a vertical longitudinal section of a sufficient portion of a tank and a flushing-valve embodying my invention to enable my invention to be understood. Fig. 2 is a top or plan view of the valve-seat, the valve being removed; Figs. 3 and 4, details to be referred to, and Fig. 5 a detail showing the 30 valve as open.

A represents the bottom of a tank of any usual construction, such as now commonly employed in water-closets. The tank-bottom A is provided with an opening or orifice, into 35 which is screwed or otherwise secured a nipple a of a preferably cylindrical casting or shell a', forming the discharge or outlet orifice for the tank, the edge a² of the said shell forming the valve-seat.

40 The casting or shell a' is provided with a hollow cross-bar a³, preferably extended diametrically across said shell, and provided, as herein shown, with upturned arms or nozzles a⁴, which are preferably extended above the 45 valve-seat, for a purpose to be hereinafter described.

The hollow cross-bar a³ is provided near its center, as herein shown, with a nipple b, which extends up into a tube or pipe b', herein shown 50 as screwed into a threaded flange or collar b² on the said cross-bar.

The tube or pipe b' is made of considerable length to extend up into the tank, and the said pipe has fitted upon or over it a hollow spindle or pipe b³, of larger diameter than the 55 pipe b', to form with the said pipe an outlet-passage b⁴ of small or contracted area.

The spindle or pipe b³ is made longer than the pipe b', and has secured to or forming part of it at its upper end, as herein shown, a 60 hollow cap or bell-shaped casting b¹⁴ of such size that its lower edge or rim lies below the top of the pipe b'. The hollow spindle at its lower end is inserted through and secured to a metallic disk or plate d, provided with, preferably, a series of slots or openings d'.

The metallic disk d has fitted upon it a leather or other washer d², constituting the valve, the said washer being provided at or near its circumference with an annular groove 70 d^x, (see Fig. 5,) into which the edge of the casting a' extends when the valve is closed or seated.

The hollow spindle is surrounded by a pipe e of larger diameter, which is herein shown 75 as screwed upon an annular flange e^x of a disk or plate e¹⁰, fitted upon the valve d², the said pipe constituting the overflow-pipe and forming with the spindle b³ an overflow-passage e', which communicates through the slots 80 d' with the outlet a of the tank.

The pipe b' is provided, as shown, with a ball-valve e², normally resting upon the top of the nipple b, the vertical movement of the said valve being limited, preferably, by a wire 85 e³, extended across the pipe b'.

The bell-shaped casting or cap b¹⁴ has fastened to it one end of the ordinary pull-chain e⁴, only a portion of which is shown in the drawings, but which may be of ordinary construction.

In operation the valve d² is raised from its seat by pulling upon the chain e⁴, thus permitting the water in the tank to flow through the shell a' into the discharge-pipe connected 95 with the basin. (Not shown.) As the valve is raised, water is drawn through the hollow arms a⁴ and cross-bars a³ into the pipe b', and when the pressure is relieved from the pull-chain the water in the pipe b' is prevented 100 from running back by the ball-valve e², which closes the nipple b, so that when the valve d²

closes by gravity the excess of water drawn into the pipe b' is forced down through the passage b^4 into the hollow casting or shell a' , and thence into the discharge-pipe. In this 5 manner the valve is made to operate as a slow-closing valve.

By extending the bell-shaped casting or cap b^{14} below the upper end of the pipes b' e a water seal or trap is formed as a safeguard 10 against sewer-gas entering the house or building.

In case of accident to the supply-valve the surplus water admitted to the tank is permitted to pass off through the overflow-passage 15 e' and slots d' into the discharge-pipe.

It will be noticed that the pull or chain e^4 is connected to the bell-shaped cap substantially over the center of the valve, so that when pressure is exerted upon the said chain 20 the lifting power is applied to the center of the valve, thereby obviating side friction between the parts and obtaining a perfectly-balanced valve.

The hollow arms a^4 are preferably extended 25 above the valve-seat a^2 , so that when the valve is opened the impurities which settle to the bottom of the tank will not enter the said arms, but only the clear water.

It will be noticed that the valve is opened 30 a distance proportional to the amount of pull, and the use of set-screws in the tank to limit the extent of opening of the valve is obviated, and also the speed of the valve in closing is constant, and set-screws to govern the amount 35 of opening of relief-valves, as in ordinary construction, are dispensed with.

I claim—

1. In a flushing-valve, the combination, with a hollow casting or shell provided with a hollow 40 cross-bar having an outlet, of a pipe se-

cured to said cross-bar about said outlet, a hollow spindle fitted loosely over said pipe, a valve secured to said spindle and provided with a slot, an overflow-pipe, and a cap or casting secured to said spindle and extended below and covering the mouth of the said overflow-pipe, substantially as described. 45

2. In a flushing-valve, the combination, with a hollow casting or shell provided with a hollow cross-bar having an outlet and provided with arms extended above said shell, of a pipe secured to said cross-bar about said outlet, a valve to control said outlet, a hollow spindle fitted loosely over said pipe, a valve secured to said spindle and provided with a slot, an overflow-pipe, and a cap or casting secured to said spindle and extended below and covering the mouth of the said overflow-pipe, substantially as described. 50

3. In a flushing-valve, the combination, with a hollow casting or shell provided with a hollow cross-bar having an outlet, of a pipe secured to said cross-bar about said outlet, a valve to control said pipe, a hollow spindle fitted loosely over said pipe, a valve secured to said spindle and provided with a slot, an overflow-pipe, and a cap or casting secured to said spindle and extended below and covering the mouth of the said overflow-pipe, and a chain or pull connected to said cap substantially over the center of the said valve, whereby a direct pull upon the valve is obtained, substantially as specified. 65

In testimony whereof I have signed my name to this specification in the presence of two subscribing witnesses.

CHARLES HENRY DILLON.
